UNITED STATES PATENT OFFICE.

JOHN GORDON, JR., OF NEW ROCHELLE, NEW YORK.

DESIGN FOR A MECHANICAL WHISTLE OR SIREN.

No. 39,056.

Specification for Design.

Patented Feb. 4, 1908.

Application filed November 30, 1907. Serial No. 404,628. Term of patent 7 years.

To all whom it may concern:

Be it known that I, JOHN GORDON, Jr., a citizen of the United States, residing at New Rochelle, Westchester county, New York, have invented a certain new, original, and ornamental Design for Mechanical Whistles or Sirens, of which the following is a specification.

This invention relates to a new, original and ornamental design for mechanical whistles or sirens.

The figure is a view in perspective, showing my new design.

I claim,

The ornamental design for mechanical whistle or siren, as shown.

JOHN GORDON, JR.
